UNITED STATES PATENT OFFICE.

WILLIAM MILTON BROWN, OF JOHNSTOWN, PENNSYLVANIA.

CRUCIBLE-FURNACE.

1,171,500.

Specification of Letters Patent. Patented Feb. 15, 1916.

Application filed April 2, 1914. Serial No. 829,147.

To all whom it may concern:

Be it known that I, WILLIAM MILTON BROWN, a resident of Johnstown, in the county of Cambria and State of Pennsylvania, have invented a certain new and useful Crucible-Furnace, of which the following is a specification.

My invention relates to the construction of crucible furnaces for manufacturing crucible steel and the invention is designed to provide a crucible furnace of improved construction, having novel means for handling the crucibles and for supporting the crucibles while in the furnace.

Another object of the invention is to provide a crucible furnace having improved means for supporting the crucibles with the bottom thereof above the level of the bottom of the crucible heating chamber.

The invention further consists in the novel construction and arrangement of parts shown and described and specifically pointed out in the appended claims.

Referring to the drawings, forming part of this specification, Figure 1 is a plan showing a bank of crucible furnaces constructed and assembled in accordance with this invention, (the furnace covers and the crucibles not being shown for the sake of clearness). Fig. 2 is a sectional elevation, the section being taken on the line II-II of Fig. 1. Fig. 3 is a longitudinal section showing on an enlarged scale the construction of the crucible supporting and lifting mechanism, forming part of this invention.

In the accompanying drawings, the numeral 2 designates the furnaces, which as shown are arranged in two parallel rows, each furnace 2 being connected to the horizontally extending waste gas flue 3 connecting to all of the furnaces, by means of a horizontal branch flue 4, and the waste gas flue 3 is connected to one end of a horizontal stack flue 5 leading to a furnace stack (not shown).

Each furnace chamber 2 is provided with a refractory lining 6 and surrounding each of the linings 6 is a cylindrical wrought metal shell 7. A flanged opening 7^a in the side of the metal shells enables the interior of the chambers 2 to be connected with the branch flues 4, these openings also having a refractory lining. The metal shells 7 and the linings 6 therein are supported on bottom plates 8, one of which extends horizontally between the adjacent transversely

extending side walls 9 which form partitions between the series of ash pits 10. One of the ash pits 10 is provided beneath each of the furnace chambers 2, and one side edge of the bottom plates 8 rests upon the ledge formed in the wall 17^a along one side of the pits 17.

The open upper end of each furnace also has a cover 11 which is formed of a metal frame work in which a refractory lining is placed. One end of the frame work is provided with track wheels 12, 12 which are rotatably secured to lugs or bearings 13 formed integrally on the cover 11. The opposite end of the frame work is provided with a lug 14 having recess or hole 15 in which one end of a bar is inserted when placing the cover in position over the top of the furnace or when moving the cover from such position to uncover the top of the furnace.

Positioned in the bottom of each furnace is a furnace grate 16 having a central opening therein and having a series of perforations or slots 16^a surrounding the central opening, to permit ingress of air and the discharge of ashes from the interior of the furnace into the ash pit 10.

The ash pits 10 beneath the furnaces 2 are connected at one end to the pit 17 which extends lengthwise in front of each row of furnaces.

Beneath each of the furnaces 2 and its ash pit 10 is a cylinder pit 18 the cylinder pits being connected together so as to form, in effect, a tunnel extending lengthwise below each of the two rows of furnaces.

The floor 19 which separates the ash pits 10 from the cylinder pits 18, is supported upon metal floor plates 20, these plates having a central opening therein and an annular upwardly extending flange 21 surrounding the opening which forms a guide for the vertically movable cylinders 22 forming part of the crucible lifting mechanism.

Secured in the bottom of the cylinder pits beneath each furnace 2 is a stationary plunger or ram 23 which is secured upon a suitable foundation therefor. The rams 23 each have an axial opening 24 therein connected by a transverse opening 25, which is at or adjacent to the lower end of the ram so as to form a port or inlet opening 11^a for the fluid pressure used in actuating the crucible lifting mechanism. (See Fig. 3.)

The inlet opening 25 is connected through a three way valve to a source of fluid pressure supply and the exhaust outlet on the valve is made of such size so as to choke 5 the escape of fluid pressure and in this way prevent too rapid descent of the cylinder 22 and crucibles 31 mounted thereon into the furnace 2 when lowering the crucibles into position within the furnace. In this 10 way compressed air or other gaseous fluid pressure may be used in operating the cylinder as a substitute for water.

Mounted on each ram 23 so as to move vertically relative thereto is a fluid pressure 15 cylinder 22, this cylinder being provided on its lower end with a stuffing box 26 and gland 27 of the usual known construction.

The upper end of the cylinder 22, which projects through the opening in the annular 20 flange 21 on the floor plate 20 supporting the floor of the ash pit 10 and through the central opening in the grate 16 forming the bottom of each furnace is provided with a reduced portion 28 forming a shoulder or 25 jog on which an annular metal ring 29 is mounted. Positioned on top of the reduced portion of the cylinder is a shape brick 30 formed of refractory material, this brick engaging with and supporting the crucibles 30 31 so that the bottom of the crucibles are held slightly above the plane of the upper surface of the grates 16 in the furnaces 2.

The cylinder 22 is provided with a renewable wrought metal shield 32 this shield 35 as shown being conveniently formed of a piece of wrought metal pipe. The shield serves to protect the cylinder from the effects of the heat of the furnace when the cylinder is projected upwardly to remove 40 a crucible from the furnace or to receive a crucible to be lowered into the furnace and also serves as a guiding surface for the vertically movable cylinder.

The lower end of the cylinder 22 is provided with a split ring 33 having flanges or lugs 34 thereon, this ring being made in sections to enable its being detachably secured to the cylinder.

Extending upwardly from the base plate 50 35 by which the plunger is secured on its foundation, are two similarly constructed rods 36 these rods extending through openings in the lugs 34 of the ring 33 on the lower end of the cylinder 22 and forming 55 stops by which the upward and downward movement of the cylinder is limited. Helical springs 37, 38 are placed on the rods 36 on opposite sides of the lugs 34 to cushion the cylinder 24 in bringing the cylinder 60 to a stop at the end of its vertically upward and downward movements. The nuts 39 on the screw threaded upper ends of the bolts 36 provide means for adjustably limiting the extent of upward movement of the 65 cylinder 22.

The furnace is fired with coke in the usual manner and air is supplied or allowed to enter through the grate in the bottom of the furnace in the same way as in existing furnaces the furnace stack creating 70 the necessary draft and collections of ashes are removed from time to time from the ash pits 10, through the pits 17 in the usual known manner.

In the operation of my improved furnace 75 the operating valve (not shown) which is connected to the inlet 25 on the lower end of the plungers 23 is turned to admit fluid pressure to the lifting cylinder 22 and the cylinder is thereby raised until its upper end is at about the floor level or top of the furnace 2. A crucible 31 is then placed on top of the cylinder, the crucible being filled 80 steel making material. The operating valve is then turned to permit the fluid pressure 85 within the cylinder to escape, the weight of the cylinder 22 and crucible 31 and the materials in the crucible being sufficient to overcome the friction of the packing rings in the stuffing box 26 of the cylinder and 90 cause the cylinder to descend until the crucible is in the position shown in Fig. 2 of the drawings. The crucible is then heated in the usual manner and is maintained at the proper temperature for the time interval 95 necessary to complete the refining operation. After the heat of steel is completed, fluid pressure is again admitted to the cylinder 22 as has been described so as to again cause the cylinder to rise and thereby lift the 100 crucible 31 into position above the top of the furnace where it is readily engaged by the tongs used in conveying the heated and filled crucibles to and from the furnaces. The above described operations are then 105 repeated with each of the series of furnaces from time to time as becomes necessary in the steel making operations.

The advantages of my invention will be apparent to those skilled in the art. By 110 the novel arrangement of the plate jacketed furnace separate units are provided and the use of common party walls to separate the joining furnace chambers is avoided. The lifting mechanism enables the crucibles to be introduced into the furnace without exposing the melters to the extreme heat of the furnace as with the old type of crucible furnaces.

The use of a stationary plunger and lengthwise movable cylinder provides an 115 outside packed cylinder and the stuffing box and gland is removed to a remote position away from the intense heat of the furnace where it can be repaired without inconvenience.

The use of the shield around the cylinder affords a renewable wearing surface which 120 can be easily and quickly renewed when 125 badly scored or worn by reason of being moved through the bed of fuel within the 130

furnace in the crucible raising and lowering operations. The stop and springs on the stop provide means for bringing the cylinder to rest without damage to the cylinder 5 and connected moving parts.

Modifications in the construction and arrangement of the parts may be made without departing from my invention.

The construction of the crucible lifting mechanism may be changed, the lifting apparatus may be used with furnaces of different construction, and the furnace is adapted for use without employing the lifting mechanism, within the scope of the appended 15 claims.

I claim:

1. A crucible furnace comprising in combination, a crucible heating chamber, having an opening in the bottom thereof, vertically 20 movable crucible supporting means extending through said opening into the heating chamber, and mechanism for elevating said supporting means to lift the crucibles to the level of the top of the furnace, said supporting means having a reduced upper end 25 forming a shoulder thereon, an annular ring on said reduced portion, and a refractory

block on the top of said ring having a reduced portion extending into the ring on the top of said crucible supporting means. 30

2. A crucible furnace comprising in combination, a crucible heating chamber, having an opening in the bottom thereof, vertically movable crucible supporting means extending through said opening into the heating 35 chamber, and mechanism for elevating said supporting means to lift the crucibles to the level of the top of the furnace, said supporting means having a reduced upper end forming a shoulder thereon, an annular ring 40 on said reduced portion, a refractory block on the top of said ring having a reduced portion extending into the ring on the top of said crucible supporting means, said refractory block when lowered position being slightly above the plane of the top of 45 said heating chamber.

In testimony whereof, I have hereunto set my hand.

WILLIAM MILTON BROWN.
